FUEL FEEDING MECHANISM

Weston M. Fulton, Knoxville, Tenn., assignor to
 W. J. Savage Company, Inc., Knoxville, Tenn.,
 a corporation of Tennessee

Application June 17, 1941, Serial No. 398,500

17 Claims. (Cl. 110—101)

1

This invention relates to an improvement in fuel feeding mechanism of the character designed for the supply of coal or other solid fuel to heaters. This application is a continuation-in-part of my prior application on Stokers, Ser. No. 359,794, filed October 4, 1940 now Patent Number 2,361,836, granted October 31, 1944.

Experience has demonstrated the fact that where fuel is fed directly on top of the fuel bed in a heater, it is difficult to obtain a fuel bed 10 having a fairly level top surface. For instance, the stoker described in the patents to Vodoz, Nos. 1,863,677 and 2,075,149, causes the fuel to pile up in the center of the fuel bed, thus making the bed much thicker in its central portion 15 than it is around the periphery thereof.

Furthermore, the largest and most immediate demand for stokers of this type, is for use in heating plants that have employed hand firing heretofore, but a stoker to supply this demand, must be adaptable to a wide variety of heaters. In many heaters, the fire-bowl is located at a considerable distance back of the fire door which makes it necessary to convey the fuel a substantial distance in the heater after it has been delivered at the fire door.

Various mechanical devices have been proposed heretofore for accomplishing this purpose, but they have possessed objectionable characteristics. For instance, in Pierce patent, No. 1,277,641, high pressure steam is used to blow the fuel from the fire door entrance into the fire box. To be fairly successful, this method would require a source of high pressure steam, which is seldom if ever available in house heating plants, because, where steam is used as the heating medium, very low pressure of one or two pounds is used, and where hot water or hot air is used, steam is not available at all.

In the patent to Crosby, No. 888,875, a rotating wheel having radially extending blades is used to throw the fuel into the fire box, but the wheel is of the "undershot" type which requires the fuel to pass below the axis of rotation and this results in clogging the feeder due to the downward forcing of the fuel against the bottom of the feed trough thus allowing lumps to be caught between the descending blades of the wheel and the feed trough. If the rotation of the wheel be reversed so as to feed the fuel in an "overshot" manner, then some of the fuel is wasted, gathers in the bottom of the fuel trough, and finally causes clogging.

The object of this invention is to improve the construction of the stoker of the class described,

5 in which the objections heretofore encountered in connection with ballistic fuel feeders are completely obviated permitting the practical utilization of this type of stoker, and yet in a construction which can be manufactured economically and used practically, and in which provision is made for securing an even distribution of the fuel over the fuel bed during feeding thereof into the heater.

10 A further object of the invention is to provide for the automatic control of the feeding mechanism in response to the level of the fuel in the chamber to which it is being fed, which is accomplished by the location of a feeler member in said chamber which is operated in response to the height or condition of the material therein to control the feeding action. Provision may be made for the operation of this feeler member in contact with the body of material in said chamber to accomplish a leveling action thereof.

15 These objects are accomplished by the provision of a practical structure as hereinafter described, a preferred embodiment of which, together with modifications thereof, are illustrated in the accompanying drawings, in which:

Fig. 1 is a side elevation of the preferred form of the invention shown applied to a conventional form of heater;

Fig. 2 is a partial vertical sectional view therethrough, with parts in elevation;

Fig. 3 is a top plan view thereof;

Fig. 4 is a horizontal sectional view therethrough, on the line 4—4 of Fig. 2;

Fig. 5 is a detail vertical cross section on the line 5—5 of Fig. 2;

Fig. 6 is a detail elevation of the fuel leveling bar, taken on the line 6—6 of Fig. 2;

Fig. 7 is a perspective view of the leveling rod supporting and guiding device, detached;

Fig. 8 is a perspective view of a ballistic fuel injector, detached;

Fig. 9 is a partial vertical sectional view through a modified form of the invention, parts being in elevation;

Fig. 10 is a detail cross section through the fuel spreading and control mechanism, on the line 10—10 of Fig. 9;

Fig. 11 is a detail cross section through the passageways of the feeder, taken on the line 11—11 of Fig. 9;

Fig. 12 is a detail cross section of a guide therefor, on the line 12—12 of Fig. 9;

Fig. 13 is a partial vertical section through still

another modified form of the invention, with parts in elevation;

Fig. 14 is a detail cross section of the air conducting tube thereof, on the line 14-14 of Fig. 13; and

Fig. 15 is a vertical sectional view partly in elevation showing the invention applied to the feeding of fuel to a supply bin.

The invention is shown in connection with a heater designated generally by the numeral 1, which may be of any conventional form to which it may be desired to feed fuel by a stoker, such as a house heating furnace of the boiler or other type as desired. The furnace 1 is shown as having the usual combustion chamber 2 therein adapted to contain a fuel bed F to which fuel may be fed as desired through the usual opening 3 normally controlled by a fire door.

When the invention is applied to a heater of the type already in use, the usual fire door is removed from over the opening 3, and is replaced by a frame 4 (Figs. 3 and 4), which is secured to the heater by bolts 5. The frame 4 has two separate openings therein 6 and 7, which are arranged in side-by-side relation, and the opening 6 is covered by a small-sized fire door 8 hinged to the frame 4 at 9 and provided with a latch 10 to hold the same closed. Upon opening the door 8, access may be had to the interior of the fire chamber 2 through the opening 6. The opening 7 is adapted to receive the fuel feeding mechanism, as hereinafter described.

Referring to Figs. 1 and 2, a fuel hopper 11 is arranged in front of the heater 1, of a size to contain a predetermined quantity of fuel to supply the heater for a substantial period of time. The hopper 11 has a back wall 12 behind which is provided an enlarged compartment 13 formed between a bottom wall 14 and a top wall 15. A tubular extension 16 projects from the compartment 13 through the opening 7 substantially to the combustion chamber 2 of the heater, as shown in Figs. 2 and 4. The tubular extension 16 is secured to the heater by means of the bolts 5.

This tubular extension 16 is shown in Fig. 5 as 45 rectangular in cross section and has partitions 17 and 18 dividing the same into three superposed passageways 19, 20 and 21, respectively, the purpose of which will be hereinafter described.

The hopper 11 has an upward extension 22 adjacent the back thereof within which are mounted interfitting twin screws 23, constituting a conveyor and constructed substantially as set forth in my prior patent on Feeder, No. 2,173,414, granted September 19, 1939. A baffle plate 24 extends downward in the hopper 11 in front of the twin-screw conveyor to keep the major portion of the body of fuel in the hopper away from interference with the rotation of the conveyor screws, while allowing the fuel to be fed thereto adjacent the bottom thereof. A retention plate 25 extends vertically along the back of the conveyor 23, and is spaced from the back wall 12 of the hopper a sufficient distance to allow fuel to fall back between the retention plate and the back wall, through an opening 26 in the latter, if it should fail to be injected into the fire chamber of the heater as hereinafter described.

The upper ends of the twin screws 23 have intermeshing gears 27 and 28 (Figs. 2 and 3) fixed thereon and intermeshing with each other. A drive gear 29 meshes with the gears 27 and 28, and is fixed on the slow speed shaft of a speed reducer designated generally by the numeral 30,

this being of any well-known construction. The speed reducer 30 has a high speed drive shaft 31 which is driven by a pulley 32 thereon, connected with a belt 33 that extends to a pulley 34 mounted on the armature shaft of an electric motor 35. The electric motor 35 and speed reducer 30 are mounted on a bracket 36 secured upon the upper end of the hopper extension 22 and upon the top 15 of the compartment 13, which bracket 36 also extends over the gears 27 and 28.

Journaled in opposite sides of compartment 13 (Fig. 2) is a shaft 37 having a pulley 38 thereon connected by a belt 39 (Figs. 1 and 8) with a pulley 40 mounted on the high speed shaft 31 of the speed reducer 30, to impart a high speed rotation to the shaft 37 upon the operation of the electric motor 35.

Mounted on the shaft 37 is a fuel-injecting wheel designated generally by the numeral 41 and shown in detail in Fig. 8. The wheel 41 is constructed with an annular drum 42 with outwardly projecting annular flanges 43 thereon and having blades 44 extending transversely between the flanges 43 radially of the drum and cooperating with the flanges to form buckets or pockets therebetween.

The fuel-injecting wheel 41 is mounted in the compartment 13 beneath the lower end of a chute 45, which chute extends substantially to a point 30 approximately directly over the center of the wheel 41, so as to deliver fuel to the top thereof, the upper end of the chute 45 being connected with the retention plate 25 at the upper end of the screw conveyor 23 to receive fuel therefrom. 35 The fuel-injecting wheel 41 is arranged adjacent the forward end of the passageway 19, but spaced therefrom.

Thus, when the fuel is elevated from the hopper 11 by the twin screw conveyor 23 into the upper end of the chute 45, it is discharged directly onto the rotating wheel 41. The fuel drops into the pockets or buckets formed in the periphery of the wheel between the blades 44, and due to the high speed of rotation of the wheel, these blades exert a strong ballistic force on the fuel to throw it tangentially from the wheel 41 through the passageway 19 into the combustion chamber 2 of the heater, as shown in Fig. 2. As will be evident therein, by imparting to the wheel 41 the proper speed of rotation, and by adjusting the chute 45 to discharge the fuel onto the wheel at the proper point, the fuel can be thrown directly through the compartment 13 into the combustion chamber of the heater.

Heretofore, the ballistic type of feeders proposed have been objectionable because if fuel particles should fall onto the upper edges of the rotating blades, these particles would not have as much force imparted to them as if they had fallen in front of a blade so as to receive the full force thereof. This would allow the particles to drop around the wheel and finally fill up the space between the wheel and its enclosing housing, thus resulting in a clogging of the wheel which interferes with its proper rotation.

However, I have overcome this objection by placing the forward edge of the wheel 41 sufficiently far from the open end of the passageway 19, as well as from the inclined wall 14 of the compartment 13, to provide a liberal space therebetween so that all waste fuel which would not have sufficient force imparted thereto by the rotating blades, to inject the same through the passageway 19 into the combustion chamber of the heater, would have freedom for return move-

ment along the inclined wall 14, thence through the opening 26 into the hopper.

The waste fuel thus discharged into the hopper 11 is allowed to fall between the back wall of the hopper and the retention plate 25 to a point where it is picked up again by the conveyor 23 along with the other fuel thus elevated during the feeding operation. As pointed out above, the baffle 24 prevents the fuel from rising up around the bottom of the conveyor 23 sufficiently high so that it would prevent the free discharge of the returned fuel through the opening 26 into the hopper. Furthermore, the action of the twin screws is such as to keep the fuel level very low at the opening 26, so as to accommodate this returned fuel.

Located in passageway 20 is mechanism for causing the fuel to be deflected uniformly over the fuel bed F, as it is injected through the passageway 19 into the combustion chamber. This mechanism is shown in Figs. 2 and 4, and is illustrated more in detail and claimed in my co-pending application on Stokers, Ser. No. 359,794, filed October 4, 1940, now Patent Number 2,361,836, granted October 31, 1944.

As shown, this deflecting means includes an arm 46 extending lengthwise through the passageway 20 being carried on an upstanding support 48 to which it is pivotally connected at 49, as shown in Fig. 2. The arm 46 extends from the passageway 20 into the combustion chamber 2 of the heater where its forward end is turned downward at 50. Rigidly fixed to this inclined end 50 is a stationary baffle 51 (Fig. 4) to the opposite edges of which side baffles 52 are hinged for vertical adjusting movement relative thereto. The arm 46 is capable of vertical angular adjustment on its pivotal support 49 by screw 51, having threaded connection with the inner end of said arm and rotatably adjustable by mechanism designated generally by the numeral 62.

Provision is made also for controlling the thickness of the fuel bed F in the combustion chamber 2 of the heater, by means of a rod 76 which extends lengthwise through passageway 21, as shown in Figs. 2, 4 and 5, projecting therefrom into the combustion chamber 2 of the heater. The forward end of the rod 76 in the combustion chamber is down-turned at 77 and screw-threaded, receiving the hub portion 78 of a stirrup 79 thereon, which stirrup is adjustably connected with the down-turned end 77 for relative vertical adjustment and is adapted to be locked in place thereon by a set screw 80. The lower end of the stirrup 79 carries a feeler in the form of a round bar 81 integral therewith in position to contact the surface of the fuel in the heater and to ride thereon.

The opposite end of the rod 76 has a ball and socket connection 82 with a lever arm 83 on a shaft 84. The lower end of the shaft 84 is journaled in a bearing carried by the partition 18, while the upper end thereof extends through the top 15 and has rigidly mounted thereon a crank 85. Pivotally connected at 86 with the outer end of the crank 85 (Fig. 3) is a link 87 which is pivotally connected at 88 with the gear 28. Thus, rotation of the gear 28 causes reciprocating movement of the link 87, oscillating the crank 85 and thereby imparting oscillatory movement to the lever arm 83, thus swinging said lever arm and the inner end of the rod 76 as shown in dotted lines in Fig. 4.

To provide for the lateral oscillatory movement of the rod 76 upon the operation of the

shaft 84, said rod is pivotally supported intermediate its ends in a guiding device shown in detail in Fig. 7. This guiding device is formed of a frame 89, having a pair of concave rollers 90 journaled therein on pins 91, spaced apart a distance sufficient to receive and guide the rod 76 therebetween, which rod rides in the concave peripheral grooves of the rollers. The rollers 90 reduce the friction which would develop otherwise from the slight longitudinal movement of the rod 76 due to the arc described by the lever arm 83 in oscillating said rod.

The frame 89 has axially aligned journal pins 92 and 93 extending therefrom. The journal pin 92 is journaled in the bottom of a well 94 formed in the partition 18 (Fig. 2) into which the lower portion of the frame 89 extends. The journal pin 93 extends upward through the top 15 in which it is journaled, in alignment with a push button 95 of a push button electric switch 96. This switch 96 is of well-known construction of the type used for controlling electric circuits, in which, however the push button 95 breaks the circuit whenever it is depressed, while release of the pressure causes it to close the electric circuit automatically. The normally closed switch 96 is connected with a source of electrical supply through lines 97, while lines 98 extend from the switch to the electric motor 35, whereby the switch 96 controls the supply of current to the electric motor.

Provision is made also for manually controlling the supply of current to the electric motor 35 independently of the switch 96, for which purpose I have provided a switch 99 connected in parallel with the switch 96 through wires 100 leading directly from the power lines 97 to the switch 99, thence to the wires 98, as shown in Fig. 2. The switch 99 is constructed for manual operation, and is adapted for use in testing the operation of the stoker while adjusting the various working parts at the time of installation. It is also of convenience if and when it should become necessary to remove large clinkers or other foreign matter through the fire door. By closing the switch 99, the operator closes the circuit to the electric motor 35 operating the stoker mechanism, and thereby moving the round bar 81 to any desired position in the combustion chamber 2, so that it will not interfere with his actions. When the round bar 81 has been moved to such desired position, out of the way of the operator, the opening of the switch 99 stops further movement.

Before putting the stoker in operation, it is first necessary to adjust the fuel baffles 51 and 52, so as to cause the fuel to spread evenly over the fuel bed F.

Having adjusted the distribution of fuel over the grates of the heater, the device is ready for operation, and the manual switch 99 is opened, thereby stopping the electric motor 35, subject to the control of the current thereto automatically under the control of switch 96.

Assuming that fire has been started in the heater but that the level of the fuel bed is at or below that shown in full lines in Fig. 2, the bar 81 rests on top of the fuel bed, and by reason of its weight, said bar will pull downward on the rod 76, moving the guiding frame 89 to its lowermost position, such downward sliding movement being permitted by the guiding of the pivot pins 92-93. This moves the pin 93 out of pressure engagement with the switch button 95, permitting the switch 96 to snap into a closed position, thus

supplying current from the wires 97 to the wires 98 to energize the electric motor 35, operating the moving parts of the stoker mechanism as described above.

The oscillating movement of the rod 76, as indicated in dotted lines in Fig. 4, causes the bar 81 to be dragged back and forth across the top of the fuel bed, leveling the surface of the fuel deposited thereon. As additional fuel is being injected into the combustion chamber, the top of the fuel bed rises gradually which lifts the bar 81, pushing the inner end of the rod 76 upward to the dotted line position in Fig. 2. This raises the guide 89-90 until the pivot pin 93 thereof presses upward against the switch button 95 and the switch 96 snaps into open position, breaking the circuit to the electric motor 35, thus stopping the operation of the stoker.

As the fire continues to burn, the consumption of fuel causes the top of the fuel bed to be lowered until the bar 81 is moved downward to the full line position in Fig. 2, which will pull downward on the arm 76, lowering the guide 89-90 away from pressure engagement with the switch button 95, closing the circuit to the electric motor 35, and operating the stoker mechanism as described above.

The oscillatory movement of the rod 76 about the vertical axis of the guide 89-90, as a fulcrum, with its inner end in the combustion chamber 2, causes the round bar 81 to be dragged back and forth over the surface of the fuel bed F, as will be evident from Fig. 6, where the dotted line positions represent the two extreme limits of the oscillation. The ball and socket connection 82 permits of the slight twisting action of the rod 76 caused by the parts 77, 79 in assuming the angular positions indicated. The dragging of the round bar 81 back and forth over the surface of the fuel bed F aids in maintaining this surface substantially level and in distributing the fuel thereover.

It will be understood that the bar 81 can be adjusted to maintain the fuel bed of different thicknesses, by screwing it up or down on the threaded portion 77 of the rod 76. After making such adjustment, the set screw 80 is tightened to hold the stirrup 79, carrying the bar 81, in its adjusted position on said rod, and with the axis of the bar 81 substantially in the direction shown in Fig. 2.

A modified form of the invention is shown in Figs. 9 to 12, which is especially adaptable to installations where the height of the fire door opening is relatively small as compared with its width, thus permitting the hopper extension opening to be extended laterally relative to its height.

In this form of the invention, the hopper structure is shown as constructed substantially identical with the construction illustrated in Figs. 1 to 8, as described above, but the tubular extension from the hopper, designated generally by the numeral 101, is divided by partitions 102 and 103 into passageways 104, 105 and 106. The passageway 105 is above the passageway 104, while the passageway 106 is arranged at one side thereof, as shown in Fig. 11. Fuel is injected through the passageway 104 into the combustion chamber 2a from the ballistic fuel injector 41a operated by the electric motor 35a as described above, which fuel is deflected in the combustion chamber 2a by baffle structure designated generally by the numeral 107 which corresponds with that shown in Fig. 2, and which is supported by means extending through the passageway 105.

When the electric motor 35a is energized, it operates gearing for driving the conveyor screws in the hopper, including a gear 28a. A connecting rod 108 is attached to the gear 28a through a ball and socket pivot 109, and at its opposite end, said connecting rod 108 has a similar ball and socket pivot 110 with the upper end of a walking beam 111. The walking beam 111 is pivotally supported at 112 in a side of the hopper 10 extension 101, in position to project at its upper end through the top of said hopper extension, and with its lower end located adjacent the bottom thereof as shown in Fig. 9.

Mounted in the passageway 106 is a push rod 113 which extends lengthwise into the combustion chamber 2a. The forward end of the push rod 113 has suspended therefrom a feeler in the form of a transverse bar 114 pivotally supported by the push rod at 115 but fixed thereto. The transverse bar 114 is adapted to bear upon the top surface of the fuel bed and to be moved transversely thereof, as shown in Fig. 9.

The push rod 113 has a bifurcated rear end 116, with a journal pin 117 mounted therein and having a peripherally grooved roller 118 journaled thereon, as shown in Fig. 12, which roller is disposed within the bifurcation 116 and is adapted to support the rear end portion of the push rod 113. The roller 118 has a concave periphery which is received between two horizontal bars 119 with sufficient looseness so that the roller may move freely lengthwise of the bars while being guided thereby. The bars 119 have laterally bent opposite end portions secured at 120 to a side wall of the hopper extension 101.

The journal pin 117 has reduced end portions extending beyond the sides of the roller 118, which extensions are received in the sides of the bifurcated end 116 of the push rod 113. Said reduced end extensions also engage within pairs of laterally spaced slotted bifurcations 121 formed on the lower end of the walking beam 111, which pairs of bifurcations are spaced apart laterally to embrace the roller 118, with the slot in each bifurcation receiving one of the end projections on the journal pin 117. This forms a pivotal connection between the walking beam 111 and the push rod 113 which allows relative movement between these parts.

The push rod 113 is also supported and guided by a pair of spaced grooved rollers 122 which are journaled in a frame 123, forming a guide that is constructed and operated substantially identical with the frame 89-90 described above, except that the push rod 113 is preferably rectangular in cross section as shown in Fig. 10, and therefore the grooves in the rollers 122 are also rectangular instead of concave in cross section. Furthermore, the frame 123 has the pivot pins 124 and 125 thereof journaled in opposite sides of a U-shaped frame 126 as shown in Fig. 10, which U-shaped frame also supports the push button switch 127 just above the end of the upper pivot pin 125. The U-shaped frame is supported on an adjusting screw 128 journaled in opposite sides of the passageway 106 through the upper end of which said adjusting screw extends and is provided with a handwheel 129 fixed thereon for rotating the screw.

It will be evident that by turning the adjusting screw 128, the entire mechanism carried by the U-shaped frame 126 can be raised and lowered. Since the rear end of the push rod 113 cannot move vertically, being held in place between the bars 119, this raising and lowering of the rollers

122 will cause the forward end of the push rod 113 to rise or fall, thereby adjusting the height of the bar 114 in the combustion chamber 2a, to vary the thickness or height of the fuel bed in the heater as may be desired under different conditions.

As shown in Fig. 9, the conducting wires pass through insulating sleeves 130 in the top wall of the hopper extension 101 and have sufficient slack by coils within the passageway 106, so as to allow this vertical movement of the switch 121 as the latter is adjusted up and down upon the U-shaped frame 126.

Since the switch 121 is constructed, as described above in connection with the switch 96, so that pressure exerted on the push button thereof breaks the electric circuit while release of this pressure allows the switch to close the circuit, it will be evident that when the fuel level in the combustion chamber 2a is sufficiently low to allow the bar 114 to pull downward on the forward end of the push rod 113, this will cause the guide frame 123 to move downward in the U-shaped frame 126, and thereby withdraw the pivot pin 125 from pressure engagement with the push button of the switch 121. This allows the switch to close the circuit and start the electric motor 35a.

The operation of the electric motor will drive the gearing including gear 28a which will cause the link 108 to operate the walking beam 111, thereby imparting reciprocating movement to the push rod 113. This will cause the bar 114 to be drawn back and forth across the top of the fuel bed in the combustion chamber, and at the same time, the injection wheel 41a will be operated to feed fuel into the combustion chamber on top of the fuel bed as described above. This causes the fuel bed to build up, gradually raising the bar 114 which moves on the surface thereof, thus gradually tilting the push rod 113 higher until it forces the frame 123 upward sufficiently to press the pivot pin 125 into pressure engagement with the push button on the switch 121, operating the latter to break the electric circuit to the motor 35a.

As the fuel bed burns down and allows the bar 114 to pull downward on the forward end of the push rod 113, the reverse operation takes place, and additional fuel is fed to the combustion chamber 2a. The dragging of the bar 114 back and forth on the surface of the fuel aids in maintaining the top of the fuel bed level. This leveling member may be constructed of any desired shape suitable for the purpose, a round bar, or a sphere, or the like.

Figs. 13 and 14 illustrate another modified form of the invention in which provision is made for cooling the fuel level control member, and also showing a different form of fuel injector.

Mounted in the combustion chamber 2b of the heater is the fuel level control and feeler member 132, which is hollow and has a hollow tube 133 connected therewith and supporting said member 132. The tube 133 is circular in cross section, as shown in Fig. 14, and is divided by a longitudinal partition 134 into separate conduits or passageways 135 and 136 communicating at their lower ends with the interior of the member 132.

A fitting 137 is secured to the top wall 15b with its open end in communication with the atmosphere and is connected with a flexible metal hose 138, leading to another fitting 139, which connects the same with the upper end of passageway 135 for supplying air thereto.

The partition 134 extends only partway to the upper end of the tube 133, but said end is closed

5 by an end wall 140, inwardly of which, a fitting 141 is connected with the tube 133 and with a flexible metal hose 142 leading to a pipe 143 which passes upward through the wall 15b and is in open communication with smoke pipe 144 of the heater 1b.

The closed end 140 of the tube 133 is rigidly attached to a rod 145 which has a ball and socket connection 82b with an arm 83b of a shaft 84b, which is operated from electric motor 35b in the manner described above in connection with Fig. 2. The tube 133 is rigid and is supported and guided intermediate its ends by movably mounted rollers 90b, the function and manner of operation of which are substantially the same as the corresponding parts described in connection with Fig. 2, while the oscillating movement of the tube 133 is substantially the same in function and result as that of the rod 76 described. The flexible tubes 138 and 142 permit of this free oscillation.

20 The draft of the smoke pipe 144 is sufficient to impart a suction in the pipe 143 which sucks air through the fitting 137, hose 138, passageway 135, down into and through the member 132, thence through passageway 136, hose 142 and pipe 143 to the smoke pipe 144. This circulation of relatively cold air through the member 132 substantially reduces its temperature and prevents it from becoming heated exclusively. This may be desirable on large commercial boilers where forced draft produces very high temperatures in the fuel bed which might prove injurious to the member 132.

25 30 35 The operation of this type of injector is substantially the same as the injector 41. The belt 147 is driven at high speed from the belt 150, and as the fuel is dropped onto the upper run thereof, it is struck by the rapidly moving cleats 151 and injected through the passageway into the combustion chamber 2b of the heater in the manner previously described.

40 45 50 55 The other structure of the stoker shown in Fig. 13 corresponds substantially with that shown in Fig. 2, except that the injector wheel 41 is replaced with a ballistic type of injector using a belt 147 extending over pulleys 148 and 149 mounted on shafts journaled in opposite sides of compartment 13b. The pulley 148 is driven by a belt 150 from the high speed shaft of the speed reducer 30b, as described above in connection with the injector 41. The conveyor belt 147 has cleats 151 rigidly attached thereto by rivets or other fastenings for imparting injecting movement to the fuel.

60 65 70 The operation of this type of injector is substantially the same as the injector 41. The belt 147 is driven at high speed from the belt 150, and as the fuel is dropped onto the upper run thereof, it is struck by the rapidly moving cleats 151 and injected through the passageway into the combustion chamber 2b of the heater in the manner previously described.

The invention is shown in Fig. 15 as applied to mechanism for feeding fuel to the stoker hopper, where a separate bin feed is used.

75 80 85 In this connection, the mechanism for feeding the fuel to the heater is substantially the same as described above, but a relatively small stoker hopper is used, as shown at 11c to which fuel is supplied from a storage bin 160 of relatively large size and capacity. A conveyor trough 161 extends from the bin 160 into the hopper 11c, for directing material from the bin into the hopper, having an open end in the latter. A spiral conveyor 162 extends through the trough

161 being shown in the form of a conveyor screw on a shaft 163, which shaft has one end journaled in a bearing 164 at the bottom of the bin 160, while its opposite end extends transversely across the hopper 11c and is journaled in a bearing 165 mounted in the wall 24c, of the hopper 11c, with the extreme end of said shaft projecting through the wall 24c.

A bevel pinion 166 fixed on said protruding end of the shaft 163 is in mesh with a bevel gear 167 fixed on a shaft 168 extending vertically in the feeder screw compartment of the hopper 11c, beside the wall 24c. The lower end of the shaft 168 is journaled in a thrust bearing fixed in an arm 169 on a bracket 170 mounted on the wall 24c by bolts, rivets or other fastenings, the lower end of the shaft 168 extending through said bearing as hereinafter described. The upper end portion of the shaft 168 is journaled in a bearing 171 carried by a bracket 172 secured to the inner face of the hopper extension 22c, with said shaft 168 projecting slightly through the bearing 171.

A stub shaft 173 is arranged in axial alignment with the shaft 168, being journaled in a bearing 174 in the top of the hopper extension 22c. A gear 175 fixed on the upper end of the stub shaft 173 meshes with one of the gears 27c that drive the feeder screws as described above in connection with Fig. 2, driven by a gear 29c from a speed reducer 30c operated by an electric motor 35c, as described in connection therewith. Thus, the operation of the electric motor 35c to drive the feed screws and supply fuel to the heater, also operates the stub shaft 173.

This stub shaft 173 carries a clutch member 176 in position for clutching engagement with a slidable clutch member 177, slidably keyed at 178 to the shaft 168 to move axially toward and from the clutch member 176. The slidable clutch member 177 is adapted to be moved axially relative to the shaft 168 by means of a fork 179 pivotally mounted at 180 on a bracket 181 secured by rivets, bolts or other fastenings to the hopper extension 22c, externally thereof. The fork 179 extends through an opening in the side of said hopper extension into the latter, where one end of said fork engages the slidable clutch member 177 for moving the latter toward the fixed clutch member 176 on the shaft 173, against the tension of a coiled spring 182 which is interposed between said end portion of the fork 179 and the top of the hopper extension 22c. The opposite end portion of the fork 179 is pivotally connected at 183 with a plunger rod 184 carrying a soft iron core 185 of a solenoid 186. The solenoid 186 is supported on an arm 187 attached to the bracket 181 and carried thereby.

The lower protruding end of the shaft 168 has fixed thereon a crank arm 188. The free end of the crank arm 188 has a universal pivotal connection 189 with one end of a connecting rod 190, the opposite end of which connecting rod has a universal pivotal connection 191 with one end of a walking beam 192. The walking beam 192 is pivotally supported at 193 intermediate its ends in one arm of a U-shaped bracket 194, while its opposite end is pivotally connected with a rod 195 that extends substantially horizontally in the hopper 11c. The free end of the rod 195 has suspended therefrom a feeler member in the form of a bar 196. The bar 196 is adapted to be disposed substantially at the normal height of the fuel in the hopper 11c.

The rod 195 extends slidably between rollers 197 in a frame 198 having trunnions journaled in opposite sides of the U-shaped bracket 194, capable of turning movement and of bodily vertical movement relative thereto. The upper trunnion is in position to engage a switch button 199 of an electric switch 200 of the normally closed type, as described above, which switch is mounted on the upper arm of the U-shaped bracket 194. Electric wires 201 are connected with the switch 200 and adapted to be connected with a source of electrical energy, one of which wires has the solenoid 186 connected in series therein, so that upon closing of the circuit through the switch 200, the solenoid 186 will be energized. The wires 201 extend through insulating bushings 202 in the top of the hopper 11c.

The hopper 11c has a cover 203 hinged to the top thereof at 204 adapted for opening movement to gain access to this hopper and to the mechanism housed therein.

The fuel is fed from the hopper 11c by stoker mechanism, such for instance as has been described above, and normally the bar 196 rides on the upper surface of the fuel in the hopper. When the fuel level is lowered due to the feeding thereof by the stoker mechanism, the bar 196 is gradually lowered, allowing the frame 198 to move downward and withdrawing its upper trunnion from bearing engagement with the push button 199 of the switch 200. When this withdrawing action is sufficient to allow the switch 200 to close, the solenoid 186 is energized, attracting its core 185, swinging the fork 179 on its pivot 180, and pushing the clutch member 177 into clutch engagement with the member 176 fixed on the stub shaft 173.

During the initial operation of the feeding mechanism for the stoker, the rotation of the feed screws by the gears 27c also rotates the gear 175 in mesh therewith and its stub shaft 173, but due to the disengagement of the clutch members 176-177, the shaft 168 and the feeding mechanism operated thereby remains inoperative. However, upon engagement of the clutch members 176-177, the shaft 168 is rotated, thereby driving the screw shaft 163 and operating the conveyor to feed fuel through the trough 161 from the bin 160 into the hopper 11c. The size and speed of the screw conveyor 162 are so arranged and predetermined that fuel will be fed from the bin 160 into the hopper 11c at a faster rate than it is withdrawn from the hopper by the stoker feeding mechanism. Therefore, the fuel level in the hopper will rise gradually even as fuel is being withdrawn therefrom.

In the meantime, the crank 188 attached to the lower end of the shaft 168 will operate the walking beam 192 through the connecting rod 190, thus reciprocating the rod 195 and dragging the feeler bar 196 back and forth over the surface of the fuel thus being fed in the hopper 11c. This continues until the fuel level rises in the hopper sufficiently to lift the feeler bar 196 and its rod 195 sufficiently to push the upper trunnion of the frame 198 into pressure engagement with the switch push button 199, thus breaking the circuit at the switch 200. This de-energizes the solenoid 186 and allows the spring 182 to press downward on the inner end of the yoke 179, separating and disconnecting the clutch members 176-177, thus stopping the operation of the shaft 168 and discontinuing the

feeding of the fuel from the bin 160 to the hopper 11c. When the level of the fuel in the hopper drops again sufficiently to close the switch 200, the cycle of operations will be repeated.

I claim:

1. In feeding mechanism, the combination of a receptacle adapted to receive a quantity of material therein, an elongated supporting device extending transversely of said receptacle and having a feeler suspended therefrom in position to bear upon the material in the receptacle, means for reciprocating said supporting device, guide means for directing the reciprocating movement of the supporting device while permitting transverse bodily movement thereof, and means associated with said guide means and operable by the transverse bodily movement of the supporting device for controlling the feeding means.

2. In feeding mechanism, the combination of a receptacle adapted to receive a quantity of fuel therein, means for feeding fuel to said receptacle, an elongated supporting member arranged to extend over the fuel in said receptacle and having a feeler bar carried thereby, means for actuating said supporting member to move the feeler bar back and forth over the fuel in the receptacle across the middle portion of said receptacle, movable guide means for said member, and means associated with said guide means and operable by movement thereof for controlling the fuel feeding means.

3. In feeding mechanism, the combination of a receptacle adapted to receive a quantity of material, electrically-actuated means for feeding material to said receptacle, a supporting device extending into said receptacle and carrying a feeler thereon in position to bear upon the material in the receptacle, guide means for said supporting device constructed for receiving the same and mounted for bodily movement in response to displacement of the feeler, operating means for the supporting device, and means associated with the guide means and operable thereby upon said bodily movement for controlling the feeding means.

4. In feeding mechanism, the combination of a receptacle adapted to receive a quantity of material, electrically-actuated means for feeding material to said receptacle, a supporting device extending into said receptacle and carrying a feeler thereon in position to bear upon the material in the receptacle, guide means for said supporting device receiving the same therein and mounted for bodily movement in response to displacement by the feeler, means for operating the supporting device to move the feeler back and forth in the receptacle, and switch means associated with the guide means in position for operation thereby upon bodily movement in response to displacement of the feeler for controlling the feeding means.

5. In feeding mechanism, the combination of a receptacle adapted to receive a quantity of material therein, electrically-actuated means for feeding material to said receptacle, a rod member extending laterally into said receptacle and having a feeler bar suspended therefrom in position to bear upon the material in the receptacle, actuating means connected with said rod member for operating the same to move the feeler bar back and forth in the receptacle, a guide for said rod member receiving the same therethrough and guiding the movement thereof, means mounting said guide for bodily movement in response to

displacement of the rod member by the feeler bar, and electrical switching means for controlling the feeding means and arranged in position for operation by the bodily movement of the guide.

6. In a stoker, the combination of fuel supply means, an elongated supporting member adapted to extend over a fuel bed and having means for bearing upon the fuel bed, means for moving said member back and forth substantially in a horizontal direction over the fuel bed, movable guide means for said member, and means operatively associated with said guide means and operable by movement thereof for controlling the fuel supply means.

7. In a stoker, the combination of fuel supply means, an elongated supporting member adapted to extend over a fuel bed and having means for bearing thereon, means for mounting said member for up and down movement, means for moving said member back and forth substantially in a horizontal direction over the fuel bed, movable guide means for said member mounted for up and down movement with the member, and means operated by said guide in its up and down movement for controlling the fuel supply means.

8. In a heater having a combustion chamber with a fuel bed therein, the combination of fuel supply means for said heater, a rod member extending into the combustion chamber over the fuel bed and having a leveling member for bearing thereon, means for moving said rod member back and forth substantially in a horizontal direction causing movement of the leveling member over the fuel bed, a guide for said rod member mounted for vertical movement therewith, and means operated by said guide for controlling the fuel supply means.

9. In a heater having a combustion chamber with a fuel bed therein, the combination of fuel supply means for said heater, a rod member extending into the combustion chamber over the fuel bed and having a leveling member for bearing thereon, means for oscillating said rod member back and forth causing movement of the leveling member over the fuel bed, a guide for said rod member mounted for up and down movement with the rod member, electrical power means for the fuel supply means, and a switch in position for actuation by the guide upon up and down movement thereof for controlling said electrical power means.

10. In a heater having a combustion chamber with a fuel bed therein, the combination of fuel supply means for said heater, a rod member extending into the combustion chamber over the fuel bed and having a leveling member for bearing thereon, a guide for said rod member, means for mounting said guide for turning movement and for up and down movement with the rod member, electrical power means for driving the fuel supply means, means operatively connected with the power means and driven thereby for oscillating the rod member, and a switch electrically connected with the power means for controlling the same, said switch being associated with the guide in position for actuation thereby upon up and down movement thereof.

11. In a heater having a combustion chamber with a fuel bed therein, the combination of fuel supply means for said heater, a rod member extending into the combustion chamber over the fuel bed and having a leveling member for bearing thereon, a guide for said rod member, means for mounting said guide for up and down move-

ment with the rod member, electrical power means for driving the fuel supply means, means operatively connected with the power means and driven thereby for reciprocating the rod member, and a switch electrically connected with the power means for controlling the same, said switch being associated with the guide in position for actuation thereby upon up and down movement thereof.

12. In a heater having a combustion chamber with a fuel bed therein, the combination of fuel supply means, a hollow control device in the combustion chamber, means for circulating cooling air through said hollow control device including rigid conduits supporting said control device and in communication at one end therethrough, means connected with said conduits and acting thereon to move the control device substantially in a horizontal direction in the combustion chamber, flexible conduit means connected with the opposite end portions of the conduits for circulating air to and from the same in different positions of the control device, and means actuated by the control device for controlling the fuel supply means.

13. In feeding mechanism, the combination with a receptacle adapted to receive a quantity of material, of feeding means for depositing material in said receptacle, and control means for said feeding means including a feeler member adapted to contact with the top of said material in the receptacle, means for moving said feeler member back and forth substantially in a horizontal direction through the midportion of said receptacle, and means responsive to lifting movement of the feeler member by variations in the height of the material for regulating the feeding means.

14. In feeding mechanism, the combination with a receptacle adapted to receive a quantity of feeding material, of means for depositing material downwardly into the middle portion of said receptacle, and control means for said feeding means including a feeler member adapted to contact with the top of said material in the receptacle, means for reciprocating said feeler member substantially in a horizontal direction through the middle portion of the receptacle in position for contact with the material therein, and means responsive to lifting movement of the feeler member by variations in the height of the material for regulating the feeding means.

15. In feeding mechanism, the combination with a receptacle adapted to receive a quantity of material, of means for depositing material in said receptacle, and control means for said feeding means including a feeler member adapted to contact with the top of said material in the receptacle, a support for said feeler member extending transversely of the receptacle, mounting means for said support including a guide therefor and bodily movable by the support in response to variations in height of the material in the receptacle, means for moving said support bodily relative to said guide to move the feeler member back and forth substantially in a horizontal direction through the midportion of the receptacle, and means responsive to movement of said guide by the support for regulating the feeding means.

16. In a stoker, the combination with a receptacle adapted to receive a quantity of material therein, of means for feeding material to said receptacle, a device in the receptacle in position to bear upon the top portion of the material therein and mounted for transverse movement back and forth relative thereto substantially in a horizontal direction, means mounting said device for bodily lifting movement in response to variations in the height of the material, and means operative in response to said lifting movement of the device for controlling the material feeding means.

17. In a stoker, the combination with a receptacle adapted to receive a quantity of solid fuel therein, of means for feeding fuel to said receptacle, a feeler member in the receptacle in position to bear upon the top surface of the fuel therein, means mounting said feeler member for transverse movement back and forth through the midportion of said receptacle substantially in a horizontal direction for leveling the material therein and for bodily vertical movement in response to variations in the height of the material, operating means for said feeler member for moving the same back and forth, and means operative in response to said vertical movements of the feeler member for controlling the fuel feeding means.
